UNITED STATES PATENT OFFICE

JOHN B. CROFOOT, OF ARLINGTON HEIGHTS, ILLINOIS

STAPLING MEANS

Application filed September 27, 1926. Serial No. 137,885.

My invention relates to stapling means, its object being to provide improved stapling means having tines so formed that they will assume a position of great holding power when driven into an adaptable medium.

Another object of my invention is to provide stapling means of this character which may be produced in the form of a staple strip comprising individual staple units held together upon or by a suitable mounting construction.

Other objects will appear hereinafter.

The invention consists in the combinations and arrangements of parts hereinafter described and claimed.

The invention will be best understood by reference to the accompanying drawings forming a part of this specification, and in which,

20 Fig. 1 represents a top plan view of a series of independent staple units as they appear when secured in place upon a metallic mounting strip;

Fig. 2 represents a side elevation of the parts shown in Fig. 1;

Fig. 3 is a cross section taken on the line 3—3 of Fig. 2; and,

Fig. 4 is a perspective view of a metallic mounting strip.

30 In the drawings I have illustrated a mode of assembling independent staple bodies which may have the extremities of their tines bent either inwardly or outwardly. Under this mode of assembly, I provide a metallic mounting strip 27 having flanges 27', and the series of independent staple bodies 28 are held in place by means of a wire element 29 arranged across the staple bodies so that its opposite extremities 30 may be bent downwardly and inwardly upon the strip 27 as

best shown in Fig. 2. Preferably and as shown, the wire element 29 is made with intermediate bows 31 so as to be endowed with sufficient resilient action to maintain the over bent extremities 30 in place. By making the staple bodies as independent units and by detachably mounting them upon strips, in the manner illustrated, it will be evident that the staple bodies, when it is desired to effect 50 stapling operations by hand, may be removed

from the mounting strip as needed. Furthermore, the insertion of the stapling bodies in certain kinds of stapling machines is greatly facilitated through the employment of these assemblies.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent is:

1. A staple assemblage comprising a series of individual staples aligned upon a mounting strip, and means to clamp said series of staples upon said mounting strip, said means consisting of a wire having means to engage the ends of the mounting strip and provided with a plurality of transverse convolutions whereby endwise resiliency is imparted to said wire to effect a secure retention of the staples on the mounting strip.

2. A staple assemblage including a single metal mounting strip having depending flanges joined by an integral web, a series of independent staples each provided with a body portion registering in continuous contact with said integral web, said staples being held to said mounting strip by a resilient member consisting of a wire having a plurality of transverse convolutions, said wire being applied to the ends of said mounting strip, the staples having depending tines contacting with said depending flanges.

3. A staple assemblage including a single metal mounting strip having depending flanges joined by an integral web, a series of independent staples each provided with a body portion registering in continuous contact with said integral web, and means for holding said staples in place on said strip comprising a wire connected to the ends of the mounting strip and having a plurality of

transverse convolutions whereby endwise resiliency is imparted to said wire to effect a secure retention of the staples on the mounting strip.

5 In testimony whereof I have signed my name to this specification.

JOHN B. CROFOOT.
